METER BOX OR THE LIKE

Robert K. Unter, Rockford, Ill., assignor to Keystone Consolidated Industries, Inc., Peoria, Ill., a corporation of Delaware

Filed Mar. 10, 1969, Ser. No. 16,168

Term of patent 14 years

Int. Cl. D20—01
U.S. Cl. D52—3

FIG. 1.

FIG. 2.

FIG. 3.

FIG. 4.

FIGURE 1 is a perspective view of a meter box or the like, embodying my new design;

FIG. 2 is a side elevational view thereof;

FIG. 3 is a front elevational view thereof; and

FIG. 4 is a top plan view thereof.

The undisclosed side of the meter box is a mirror image of the side shown, and the rear is plain in appearance.

I claim:

The ornamental design for a meter box or the like, substantially as shown as described.
